UNITED STATES PATENT OFFICE.

HAMILTON LINDSAY, OF CLEVELAND, OHIO, ASSIGNOR TO THE LINDSAY WIRE WEAVING COMPANY, OF CLEVELAND, OHIO, A CORPORATION OF OHIO.

SEAM FOR WOVEN-WIRE BELTS.

Application filed September 15, 1922. Serial No. 588,327.

To all whom it may concern:

Be it known that I, HAMILTON LINDSAY, a citizen of the United States, residing at Cleveland, in the county of Cuyahoga and State of Ohio, have invented a certain new and useful Improvement in Seams for Woven-Wire Belts, of which the following is a full, clear, and exact description, reference being had to the accompanying drawings.

This invention relates to a method of joining the ends of a wire fabric to form an endless belt which is particularly useful in Fourdrinier paper machines. More particularly, my invention is concerned with a seam for lacing the ends of a belt having a special weave as set forth in my co-pending application Serial No. 525,403, filed December 28, 1921.

Briefly, the belt illustrated in my co-pending application embodies a fabric wherein the lower knuckles of the longitudinally extending or warp wires, pass continuously beneath two or more cross or lay wires, instead of only one. Accordingly, the warp wires are divided into groups, preferably three in number, during the weaving operation, and are manipulated so that one group forms one plane of the shed while the other two groups form the other plane of the shed, while the shuttle passes therebetween and across the loom. These groups are interchanged after each stroke of the shuttle, whereby the fabric so formed has short knuckles on the upper side of the belt and long knuckles on the lower side thereof. This results in a construction which gives a longer wearing surface to the under side of the belt, thus increasing the life thereof.

One of the difficulties encountered in joining the ends of the belt above described is the provision of a seam which does not fill the interstices (which would render it difficult for water to pass through this seam when the belt is in use) and at the same time forms a sufficient support between the ends of the fabric so as not to strain the pulp. Another difficulty is the arrangement of closing wires which do not displace the lay wire so as to distort the mesh.

Accordingly, one of the objects of my invention is the provision of a seam having sufficient space for the passage of water

therethrough, and sufficient support between the ends of the fabric so that the pulp is properly drained and at the same time supported adjacent the seam, whereby the paper is not weakened. Another object is the provision of a seam for use in a belt constructed in the manner above set forth which will not weaken the wires adjacent the ends of the fabric. Furthermore, my invention includes a seam, the wires of which lie in substantially the same plane as the warp wires so that the wear occasioned by the passage of the seam across a suction box is not greater than that occurring on other parts of the belt.

The preferred embodiment for carrying out my invention is illustrated in connection with the accompanying drawings, and is hereinafter described in detail. The essential features are summarized in the claims.

In the drawings, Figs. 1 and 2 are plan views illustrating the ends of a belt having a weave constructed according to the manner set forth in my co-pending application, and illustrating the application of a stitching wire, wherein Fig. 1 shows the top side of the belt, while Fig. 2 shows the bottom side thereof; Figs. 3 and 4 are views similar to Figs. 1 and 2 and show the application of a closing wire to the stitching wires; Figs. 5 and 6 are views corresponding to Figs. 3 and 4 with the application of a second closing wire in the nature of a reinforcement; and Figs. 7, 8, and 9 are sections taken on the corresponding lines in Figs. 1, 3, and 5 respectively.

As shown in Figs. 1 to 6, A indicates the longitudinal or warp wires of the fabric and B the transverse or lay wires. In Figs. 7 to 9, the foremost warp wire A¹ passes over the transverse wire B¹, thence beneath two transverse wires B² and B³, over the wire B⁴, and thence beneath the next two transverse wires of which one only is shown at B⁵. The next warp wire indicated at A² passes beneath the two lay wires B¹ and B², thence over the lay wire B³, thence beneath the two lay wires B⁴ and B⁵, etc. The third warp wire A³ shown particularly in Fig. 1 passes beneath the lay wire B¹, over the lay wire B², thence beneath the two lay wires B³ and B⁴, over the lay wire B⁵, etc.

The described construction is illustrated

by reference characters, particularly in the upper half of Fig. 1, but the weave is the same for all figures illustrated. With this construction then, the fourth warp wire 5 would correspond to the wire A¹, the fifth to the wire A², etc.; whereupon the lay wires lie alternately over two and beneath one warp wire, etc.

The fabric shown and described thus 10 has on its under side a series of long longitudinal knuckles in contradistinction to the short or abrupt knuckles on the upper side. Accordingly, every third warp wire adjacent the same lay wire has a short knuckle 15 on the upper side, as is shown particularly in Fig. 1, wherein the wire B⁴ has short knuckles on the top side indicated at 10 to 15, etc. Similarly, the wire B³, on the top side of the fabric, has short knuckles, 20 each positioned one warp wire to the left of those forming the short knuckles over the wire B⁴. Accordingly, the short knuckles for the wire B³ are indicated at 16 to 20, etc.

25 My invention, as heretofore stated, embodies a seam for closing the ends of a belt having a weave as heretofore described. To this end, I have shown the first step in forming the seam as embodying stitching wires C and C¹ which extend over the ends 30 of the fabric and on opposite sides thereof to form loops for receiving the closing wires as will be hereinafter described. Each stitching wire is carried back several lay 35 threads, whereby the stresses on the closing wires incident to the tension on the belt during operation, will not pull the lay threads out of the fabric. Accordingly, I 40 have shown the stitching wire C in Fig. 1 as passing over the lay wire B⁴ and to the left of the short knuckles 10 to 14. This brings the inner loops of the stitching wire over a lay wire which is held in position on one side by the short knuckles 10 to 14 and 45 on the other side by the short knuckles 16 to 20. In this way, the lay wire is not distorted when tension is placed upon the belt. The outer loops of the stitching wire C are 50 shown as passing around the wire B¹ and in such position as to avoid the knuckles on the top and bottom sides of the fabric adjacent the ends thereof. For this reason, the stitching wire is carried as indicated in 55 the upper half of Fig. 1, substantially parallel to the warp wires for about half the length of the loop. The upper half of Figs. 1 and 2 indicate the positioning of the stitching wire C on the top and bottom sides of the belt.

60 In the lower half of Figs. 1 and 2, I have shown a stitching wire C¹. In these views, the lay wires are indicated at BB¹ to BB⁵ inclusive, and the stitching wire is 65 shown as extending over the wire BB⁴ adjacent the short knuckles 10^a to 14^a respec-

tively. These knuckles are shown in the lower half of Fig. 1 as being to the left of the stitching wire. To the right of the wire C¹, and crossing the lay wire BB³, are short knuckles indicated at 16^a to 20^a respectively. Thus, the inner loops of the stitching wire C¹ cross the lay wire BB⁴ intermediate two short knuckles whereby the lay wire BB⁴ is not distorted when tension is placed upon the belt. Similarly the wire C¹ is laid so as to avoid the knuckles whereby in the finished seam the stitching wire lies in the same plane as the warp wires. Referring particularly to Fig. 2, it will be seen that the stitching wires on the under side of the fabric lie substantially parallel to the warp wires, thus reducing the diagonal stresses on the lay wires B⁴ and BB⁴ to a minimum when the belt is in use.

70 In Figs. 3 and 4, I have shown the next 75 step in the making of the seam, namely the application of the closing wire. This closing wire is indicated at D, as extending between the loops formed by the stitching wires C and C¹; the weave being such that 80 the closing wire passes on opposite sides of the fabric through the loops on every third mesh. In Fig. 3, the top side of the belt shows the closing wire D extending 85 across the continuation of two warp wires, while the under side indicated in Fig. 4 shows the closing wire passing over the continuation of only one warp wire. In 90 this way, the closing wire on the bottom side is more nearly parallel to the warp 95 wires, and at the same time does not cross a knuckle.

100 A belt having a stitching wire at each 105 edge of the seam and a closing wire, as indicated, may have sufficient rigidity for use, but it is preferable to employ a reinforcing wire in the nature of a second closing wire as indicated at E in Figs. 5 and 6. In the lower half of Fig. 5, this closing wire is 110 shown as passing between the same warp wires through which the stitching wire C¹ extends except that the loops for the wire E 115 extend over the lay wire BB². On the opposite end of the belt however, the loops for the wire E pass over the wire B² and one row to the left of that occupied by the inner loops of the stitching wire C. Accordingly, 120 the wires C, C¹, D and E lie in substantially the plane of the warp wires on both sides of the belt. It will further be noticed that in the upper half of the fabric in Fig. 5, the wires C, E and D each occupy a different 125 row and are positioned in every third interstice or row. In the lower half however, two of the wires, namely C¹ and E, occupy 130 the same row, while the wire D occupies the row to the left of that occupied by the wires E and C¹. In this connection the term "row" means the interstices or mesh intermediate two adjacent warp wires.

Referring now to Fig. 6 wherein the lower side of the belt is shown, the second closing wire extends from one end of the belt, across the continuation of one warp wire, and then 5 over the wire B² on the opposite end thereof. By making the closing wires extend across a continuation of only one warp wire on the under side of the belt, I provide a seam wherein the stitching and closing wires are 10 all nearly parallel, and at the same time I provide a connection which does not tend to displace the lay wires when the belt is in use. Moreover, the reinforcing wire E serves to close the space between the ends of the 15 belt whereby the paper formed adjacent the seam is not weakened.

A seam constructed according to my invention transmits the operating stresses to 20 lay wires remote from the ends of the belt and at the same time provides an anchorage adjacent short knuckles, whereby movement or displacement of any lay wire is prevented. The proper drainage is not interfered with, and at the same time the pulp is properly 25 supported. A further feature set forth by my invention is the positioning of the stitching and closing wires so as to maintain the wires forming the seam within the same plane as the warp wires. In this way, the 30 wear on the seam and cloth is substantially uniform.

I claim:—

1. A seam for an endless belt wherein the weave comprises warp wires and lay wires, 35 the warp wires having long knuckles on one side of the belt and short knuckles on the other side thereof, having a closing wire extending from one end across the seam opening to the other end and over lay wires, the 40 lay wire on one of the ends having a portion of a short warp knuckle adjacent the closing wire.

2. A seam for woven wire belts, wherein the weave comprises warp wires and lay wires, the warp wires having long knuckles on one side of the belt and short knuckles on the other side thereof, having a closing wire extending from one end of the belt across the seam opening to the other end thereof and over lay wires, at least one of the 50 lay wires having a portion of a short warp knuckle adjacent the closing wire said short knuckle being positioned intermediate the opening through which the closing wire passes and the end of the belt.

3. A seam for an endless belt wherein the weave comprises warp wires and lay wires, the warp wires having long knuckles on one side of the belt and short knuckles on the other side thereof, having a wire extending 55 over a lay wire and intermediate two warp wires, one of the warp wires having a short knuckle over said lay wire and the other of said warp wires having a short knuckle over the adjacent lay wire.

4. A seam for woven wire belts wherein the fabric has warp wires forming long knuckles on one side of the fabric and short knuckles on the opposite side thereof, having a wire extending from the ends of the 70 fabric inwardly and over a lay wire, the warp wire on one side of the first-mentioned wire forming a short knuckle over said lay wire, and the warp wire on the other side forming a short knuckle over the next lay 75 wire toward the end of the belt.

5. A seam for an endless belt wherein the weave comprises warp wires and lay wires, the warp wires having long knuckles on one side of the belt and short knuckles on the 80 other side thereof, having a stitching wire and a closing wire passing through the fabric adjacent the ends of the belt, the stitching wire passing through the fabric over a lay wire and intermediate two warp wires, 85 one of which has a short warp knuckle over said lay wire adjacent the stitching wire, and a closing wire on at least one end of the belt passing across the ends of the belt and between two warp wires other than those 90 through which the stitching wire passes.

6. A seam for an endless belt wherein the weave comprises warp wires and lay wires, the warp wires having long knuckles on one side of the belt and short knuckles on the 95 other side thereof, having a stitching wire passing through the fabric adjacent the end of the belt and through every third row to form loops, said stitching wire passing over a lay wire remote from the end of the belt, the warp wire on at least one side of the 100 stitching wire forming a short knuckle over said lay wire, and a closing wire passing through loops formed by the stitching wire.

7. A seam for an endless belt wherein the weave comprises warp wires and lay wires, the warp wires having long knuckles on one side of the belt and short knuckles on the other side thereof, having stitching and closing wires passing through the fabric adjacent the ends to be joined, said wire passing on one end of the belt over lay wires, each of said lay wires having a warp wire on one side of the first mentioned wires forming a short knuckle, with the warp wire 110 on the other side forming a short knuckle 115 over the adjacent lay wire.

8. A seam for an endless belt wherein the weave comprises warp wires and lay wires, the warp wires having long knuckles on one side of the belt and short knuckles on the other side thereof, having stitching and closing wires passing through the ends of the belt, such stitching and closing wires occupying different rows on one end of the 120 belt, and occupying the same row on the other end of the belt.

9. A seam for woven wire belts, wherein the weave comprises warp wires and lay wires, the warp wires having long knuckles 125

on one side of the belt and short knuckles on the other side thereof, having stitching and closing wires passing through the ends of the belt, said wires occupying different rows on one end of the belt and occupying the same row on the other end of the belt, and all of said wires passing through the fabric over lay wires which have a short knuckle on one side of said stitching and closing wires.

10. A seam for an endless belt, wherein the weave comprises warp wires and lay wires, the warp wires having long knuckles on one side of the belt and short knuckles on the other side thereof, having a stitching wire and two closing wires passing through the fabric adjacent the ends of the belt, all of said wires passing through different rows on one end of the belt.

15. A seam for an endless belt, wherein the weave comprises warp wires and lay wires, the warp wires having long knuckles on one side of the belt and short knuckles on the other side thereof, having a stitching wire and two closing wires passing through the fabric adjacent the ends of the belt, the stitching and one closing wire on end of the belt occupying the same row.

20. A seam for an endless belt, wherein the weave comprises warp wires and lay wires, the warp wires having long knuckles on one side of the belt and short knuckles on the other side thereof, having a stitching wire and two closing wires passing through the fabric adjacent the ends of the belt, all of said wires passing through different rows on one end of the belt, and two of the wires passing through the same row on the other end of the belt.

25. A seam for an endless belt wherein the weave comprises warp wires and lay wires, the warp wires having long knuckles on one side of the belt and short knuckles on the other side thereof, having a stitching wire and two closing wires passing through the fabric adjacent the ends of the belt, all of said wires passing through different rows on one end of the belt, and at least one of said wires passing over a lay wire which has a short warp knuckle adjacent thereto.

30. A seam for an endless belt, wherein the weave comprises warp wires and lay wires, the warp wires having long knuckles on one side of the belt, and short knuckles on the other side thereof, having a stitching wire and two closing wires passing through the fabric adjacent the ends of the belt, the stitching and one of said closing wires occupying the same row on one end of the belt, but passing over different lay wires, and each of said lay wires having a portion of a short warp knuckle adjacent the first mentioned wires.

35. A seam for an endless belt wherein the weave comprises warp wires and lay wires,

the warp wires having long knuckles on one side of the belt and short knuckles on the other side thereof, having a stitching and two closing wires passing through the fabric adjacent the ends of the belt, all of said wires on one end of the belt passing through different rows and over different lay wires.

40. A seam for an endless belt, wherein the weave comprises warp wires and lay wires, the warp wires having long knuckles on one side of the belt and short knuckles on the other side thereof, having a stitching wire and two closing wires passing through the fabric adjacent the ends of the belt, all of the wires on one end of the belt passing through different rows and over different lay wires, and the stitching wire and one closing wire on the other end of the belt occupying the same row, with the other closing wire occupying a different row.

45. A seam for woven wire belts, wherein the weave comprises warp wires and lay wires, the warp wires having long knuckles on one side of the belt and short knuckles on the other side thereof, having a stitching wire extending around the ends of the belt to form loops, and a closing wire extending through the loops, said closing wire passing on one side of the fabric over a continuation of two warp wires and on the other side over a continuation of one warp wire.

50. A seam for an endless belt, wherein the weave comprise warp wires and lay wires, the warp wires having long knuckles on one side of the belt and short knuckles on the other side thereof, having a stitching wire passing over a lay wire, and through every third row to form loops, said lay wire having a portion of a short knuckle on each side of the loop, and having a closing wire through the loops formed on the stitching wire, said closing wire occupying rows different from those occupied by the stitching wire.

55. A seam for woven wire belts, wherein the weave comprises warp wires and lay wires, the warp wires having long knuckles on one side of the belt and short knuckles on the other side thereof, having stitching and closing wires passing through the fabric adjacent the ends of the belt in such manner that some of the wires pass through the fabric adjacent the short knuckles and also in such manner that such wires lie approximately parallel to the warp wires on one side of the fabric.

60. A seam for woven wire belts, wherein the weave comprises warp wires and lay wires, the warp wires having long knuckles on one side of the belt and short knuckles on the other side thereof, having closing wires extending over the ends of the belt and over lay wires, said lay wires having at least one short knuckle passing thereover adjacent the interstices through which the clos-

- ing wires extend, said closing wires passing on one side of the belt over the continuation of one warp wire and passing on the other side of the belt over the continuation of two 5 warp wires.
21. A seam for an endless belt, wherein the weave comprises warp wires and lay wires, the warp wires having long knuckles on one side of the belt and short knuckles 10 on the other side thereof, having two closing wires passing across the ends of the belt, at least one of the wires passing over a lay wire, said lay wire having a short knuckle adjacent thereto, and said closing 15 wires occupying different rows on both ends of the belt.
22. A seam for an endless belt wherein the weave comprises warp wires and lay wires, the warp wires having long knuckles on one 20 side of the belt and short knuckles on the other side thereof, having two closing wires passing across the ends of the belt, said wires occupying different rows and passing over different lay wires.
- 25 23. A seam for an endless belt wherein the weave comprises warp wires and lay wires, the warp wires having long knuckles on one side of the belt and short knuckles on the other side thereof, having two closing 30 wires passing across the ends of the belt, said wires occupying different rows and passing over different lay wires and both of said closing wires passing over a continuation of one warp wire on one side of the 35 fabric and over a continuation of two warp wires on the opposite side of the fabric.
24. A seam for an endless belt, wherein the weave comprises warp wires and lay 40 wires, the warp wires having long knuckles on one side of the belt and short knuckles on the other side thereof, having a stitching wire and two closing wires passing through the fabric adjacent the ends of the belt, and in such manner that on one end of the belt, the stitching and closing wires occupy different rows and pass over different lay wires, while on the other end of the belt two of the wires occupy the same row, 45 but all pass over different lay wires, and the closing wires on one side of the belt pass over a continuation of one warp wire, while on the other side of the belt over a continuation of two warp wires, whereby 50 said stitching and closing wires lie in the same plane as the warp wires.
- 55 25. A seam for an endless belt, wherein the weave comprises warp wires and lay wires, the warp wires having long knuckles on one side of the belt and short knuckles on the other side thereof, having stitching 60 and closing wires passing through the ends of the belt, with one of the wires extending over a lay wire which has a short knuckle adjacent thereto, said stitching and closing 65 wires occupying different rows on one end of the belt.
26. A seam for an endless belt, wherein the weave comprises warp wires and lay wires, the warp wires having long knuckles 70 on one side of the belt and short knuckles on the other side thereof, having stitching and closing wires passing through the ends of the belt, at least one of the wires passing over a lay wire having a short knuckle 75 adjacent thereto, said stitching and closing wires occupying the same row on one end of the belt.
27. A seam for an endless belt wherein the weave comprises warp wires and lay 80 wires, the warp wires having long knuckles on one side of the belt and short knuckles on the other side thereof, having stitching and closing wires passing through the ends of the belt, the stitching wire passing 85 through the fabric over a lay wire and intermediate two warp wires, one of which has a short knuckle over said lay wire adjacent the stitching wire.
28. A seam for an endless belt wherein the weave comprises warp wires and lay 90 wires, the warp wires having long knuckles on one side of the belt and short knuckles on the other side thereof, having stitching and closing wires passing through the ends 95 of the belt, the closing wire passing through the fabric over a lay wire intermediate two warp wires, one of which has a short knuckle over said wire adjacent the closing wire.
29. A seam for an endless belt wherein 100 the weave comprises warp wires and lay wires, the warp wires having long knuckles on one side of the belt and short knuckles on the other side thereof, and having stitching and closing wires passing through 105 the fabric adjacent the ends of the belt, said wires occupying the same row on one end of the belt but passing over different lay wires, at least one of the lay wires having a portion of a short warp knuckled adjacent 110 the closing wire.
30. A seam for an endless belt wherein the weave comprises warp wires and lay 115 wires, the warp wires having long knuckles on one side of the belt and short knuckles on the other side thereof, having stitching and closing wires passing through the fabric adjacent the ends of the belt, said wires occupying the same row on one end of the belt but passing over different lay wires, at least one of the lay wires having a portion of a short warp knuckle adjacent the stitching wire.
31. In a seam for an endless belt wherein the weave comprises warp wires and lay 125 wires, the warp wires having long knuckles on one side of the belt and short knuckles on the other side thereof, a stitching wire passing over a lay wire through every third row to form loops, said lay wire having a 130

portion of the short knuckle on each side of the loop.

32. In a seam for an endless belt, wherein the weave comprises warp wires and lay wires, the warp wires having long knuckles on one side of the belt and short knuckles on the other side thereof, a stitching wire passing over a lay wire to form loops, said lay wire having a portion of the short warp knuckle on the side of the stitching wire toward the end of the belt.

33. A seam for an endless belt wherein the weave comprises warp wires and lay wires, the warp wires having long knuckles on one side of the belt and short knuckles on the other side thereof, having a closing wire extending through the ends of the belt and over lay wires, said closing wire passing on one side of the belt over a continuation of one warp wire, and passing on the other side of the belt over a continuation of two warp wires.

34. A seam for an endless belt, wherein the weave comprises warp wires and lay wires, the warp wires having long knuckles on one side of the belt and short knuckles on the other side thereof, having two closing wires passing across the ends of the belt, at least one of the wires passing over a lay wire having a short warp knuckle adjacent thereto.

35. A seam for an endless belt wherein the weave comprises warp wires and lay wires, the warp wires having long knuckles on one side of the belt and short knuckles on the other side thereof, having two closing wires passing across the ends of the belt, said closing wires occupying different rows on both ends of the belt.

36. A seam for an endless belt wherein the weave comprises warp wires and lay wires, the warp wires having long knuckles on one side of the belt and short knuckles on the other side thereof, having a stitching and two closing wires passing through the fabric adjacent the ends of the belt, at least one of said wires passing over a lay wire

which has a short warp knuckle adjacent thereto.

37. A seam for an endless belt wherein the weave comprises warp wires and lay wires, the warp wires having long knuckles on one side of the belt and short knuckles on the other side thereof, having a stitching and two closing wires passing through the fabric adjacent the ends of the belt, the stitching wire passing through the belt over a lay wire which has a short warp knuckle adjacent to the stitching wire.

38. A seam for an endless belt wherein the weave comprises warp wires and lay wires, the warp wires having long knuckles on one side of the belt and short knuckles on the other side thereof, having a stitching and two closing wires passing through the fabric adjacent the ends of the belt, one of said closing wires passing through the belt over a lay wire which has a short warp knuckle adjacent to the closing wire.

39. A seam for an endless belt, wherein the weave comprises warp wires and lay wires, the warp wires having long knuckles on one side of the belt, and short knuckles on the other side thereof, having a stitching and a closing wire passing through the fabric adjacent the ends of the belt, at least one of said wires passing through the belt over a lay wire and intermediate two warp wires, one of the warp wires having a short knuckle adjacent said lay wire.

40. A seam for an endless belt, wherein the weave comprises warp wires and lay wires, the warp wires having long knuckles on one side of the belt and short knuckles on the other side thereof, having a stitching and a closing wire passing through the fabric adjacent the ends of the belt, both of said wires passing through the fabric over a lay wire and intermediate two warp wires, and each of said lay wires having a short warp knuckle adjacent thereto.

In testimony whereof, I hereunto affix my signature.

HAMILTON LINDSAY.
